United States Patent Office

Des. 198,882
Patented Aug. 11, 1964

198,882

BOAT

John P. Barnard, Fort Worth, Tex., assignor to Terry
Plastics, Fort Worth, Tex., a corporation of Texas

Filed Feb. 3, 1964, Ser. No. 78,487

Term of patent 14 years

(Cl. D71—1)

FIG. 3.

FIG. 4.

FIG. 5.

FIG. 6.

FIGURE 1 is a perspective view of a boat showing my new design.

FIGURE 2 is a perspective view of the bottom of my design as viewed from the front.

FIGURES 3, 4, 5 and 6 are side, top, front end and rear end views, respectively, of my design.

I claim:

The ornamental design for a boat, substantially as shown.
